DESIGN FOR A TABLE

Thomas F. Murray, New York, N. Y.

Application May 11, 1933, Serial No. 48,078

Term of patent 7 years

To all whom it may concern:

Be it known that I, THOMAS F. MURRAY, a citizen of the United States, residing at New York, in the county of New York and State of New York, have invented a new, original, and ornamental Design for Tables, of which the following is a specification, reference being had to the accompanying drawing, forming part thereof.

The figure is a perspective view of the table, showing my new design.

I claim:

The ornamental design for a table as shown.

THOMAS F. MURRAY.
